(57) **CLAIM**

The ornamental design for a garment bag, as shown and described.

DESCRIPTION

FIG. 1 is a top and front perspective view of a garment bag showing our new design according to a first embodiment; FIG. 2 is a front elevation view thereof; FIG. 3 is a rear elevation thereof; FIG. 4 is a left side elevation view thereof; FIG. 5 is a right side elevation view thereof; FIG. 6 is a top plan view thereof; FIG. 7 is a bottom plan view thereof; FIG. 8 is a top and front perspective view of a garment bag showing our new design according to a second embodiment; FIG. 9 is a front elevation view thereof; FIG. 10 is a rear elevation thereof; FIG. 11 is a left side elevation view thereof; FIG. 12 is a right side elevation view thereof; FIG. 13 is a top plan view thereof; and, FIG. 14 is a bottom plan view thereof.

The broken lines illustrating hangers and garments are environment. The remaining broken lines illustrate portions of the garment bag. None of the broken lines form part of the claimed design.
